UNITED STATES PATENT OFFICE

HENRY W. PLEISTER, OF WESTFIELD, NEW JERSEY, ASSIGNOR TO HENRY B. NEWHALL CORPORATION, OF GARWOOD, NEW JERSEY, A CORPORATION OF NEW JERSEY

BOLT ANCHOR HAVING A COLLAPSIBLE HEAD

Application filed April 19, 1929. Serial No. 356,577.

My invention relates to bolt anchors and more particularly to bolt anchor shields having a collapsible head to permit the work to be drawn up flush against the surface 5 of the wall, or other support, when, for any reason, a portion of the head may protrude from the hole in which the bolt anchor shield is mounted.

My invention further relates to certain articles of manufacture, combinations, and sub-combinations, and details of construction, all of which will be more fully herein-after described and pointed out in the claims.

In the drawings, the same reference numerals refer to similar parts in the several figures:—

Figures 1 to 7 illustrate a two part lag screw collapsible shield. Figure 1 is a side elevation.

20 Figure 2 is a plan view.

Figure 3 is a vertical section, on an enlarged scale, taken on line 3, 3 of Figure 1 looking in the direction of the arrows.

25 Figure 4 is a section on line 4, 4 of Figure 2 looking in the direction of the arrows.

Figure 5 is an end view.

30 Figure 6 is a vertical section through a support illustrating the shield partially expanded, its collapsible head slightly protruding from the hole.

35 Figure 7 is a vertical section, similar to Figure 6, illustrating the final expansion of the shield and the collapsing of its head, to permit the work to be brought up flush against the support.

Figures 8, 9 and 10 illustrate a modification. Figure 8 is a side elevation.

Figure 9 is a plan view.

40 Figure 10 is a fragmentary vertical section, similar to Figure 7, but showing the head collapsed inward, rather than outward.

Figures 11 and 12 illustrate another modification. Figure 11 is a side elevation.

45 Figure 12 is a plan view of Figure 11.

Figures 13, 14 and 15 illustrate a further modification. Figure 13 is a side elevation of a one part lag shield.

Figure 14 is a plan view of Figure 13.

50 Figure 15 is a front elevation of Figure 13.

Figures 16 to 21 illustrate another modification. Figure 16 is a side elevation.

Figure 17 is a plan view of Figure 16.

Figure 18 is a longitudinal section on line 18—18 of Figure 17.

Figure 19 is a vertical section, on an enlarged scale, on line 19—19 of Figure 16.

Figure 20 is a vertical section through a support, illustrating the ductile collapsible shield or anchor partially expanded and extending out from the hole in the support.

Figure 21 is a vertical section, similar to Figure 20, with the ductile shield or anchor fully expanded and its head collapsed, to bring the work up flush against the support.

My invention relates essentially to bolt anchors, and more particularly to a shield for bolt anchors having a collapsible head, which, if it extends out slightly from the hole in which it is mounted, will permit the head to be collapsed, thereby shortening the length of the shield and permitting the work, supported by the bolt anchor, to be brought up flush against the surface of the wall of the support. This insures a first-class workman-like job with comparatively fast placing of the shield, for, with my invention, absolute accuracy in estimating the depth to which the shield must be located, to allow for any slipping or creeping of the shield, is not necessary. Should the shield protrude slightly from the hole in the wall when expanded, or partially expanded, it is not necessary to unfasten it and re-position the shield in the hole, to insure the work being brought up flush against the support.

On the contrary, should the shield protrude slightly from the hole, further movement of the expanding means will collapse the head of the shield, more or less, thereby shortening the shield and permitting the work to lie flush against the support. This not only enhances the appearance of the job but makes a firmer bond, in that the work will frictionally engage the surface of the wall of the support, which will prevent teetering or pivoting of the work on the shield.

I have shown various forms of my invention in the drawings, but it is of course to

be understood that these are merely illustrative.

In Figures 1 to 7 my shield is formed of the two sections 1, 1 secured together by the 5 malleable iron ears or lugs 2, 2. The outer ends of the members 1, 1 are provided with weakened head members 3, 3, in any suitable manner, such as by providing them with the weakened apertures 4, 4 and cutaway portions 10 5, 5.

When the co-operating expanding means, as for example, the lag screw 6, is screwed into the shield 7, it may be found that the head 8 of the shield 7 extends out slightly 15 from the hole 9 in the support 10. Ordinarily, in such cases, the work 11 would be held away from the surface 12 of the support 10, giving a very unworkmanlike and slovenly appearance to the job. To correct this, re- 20 quires a resetting of the shield 7 so that when it is again expanded, the work 11 will rest against the surface 12 of the wall.

By my invention the resetting or readjustment of the shield is avoided. It is merely 25 necessary, in my invention, to further operate the expanding member, as for example, the lag screw 6, which will cause the head 8 to collapse, more or less, shortening the length of the shield 7 and permitting the 30 work to be brought up flush against the surface 12 of the support 10, as shown in Figure 7.

This support 10 is ordinary masonry, concrete, brick, stone, terra cotta or similar material, and has to be drilled to form the hole 35 9, for the reception of the collapsible shield 7.

In Figures 1 to 7 the weakening apertures or openings are 4, 4, and the cutaway portions are 5, 5, both being so formed as to insure 40 that the collapsible head 8, will yield outwardly or radially and increase the bond or grip of the shield with the surface of the hole 9, see Figure 7, thereby preventing teetering.

45 In Figures 8, 9 and 10 I have illustrated a collapsible shield 13 having a collapsible head 14 provided with weakening openings and cutaway portions 15, 15 and 16, 16 so that when the lag, or other screw or member 6, exerts sufficient pressure the collapsible head 50 14 will collapse inward, Figure 10, rather than outward.

In Figures 11 and 12 I have illustrated another modification in which the shield 17 is 55 provided with a collapsible head 18 formed by means of the cutaway portions 19, 19. This head 18 will collapse in the same manner as previously described in connection with Figure 7.

60 In Figures 13, 14 and 15 I have shown my invention in connection with a single member lag shield 20, instead of the double form illustrated in Figures 1 to 10. In this form the expansion is produced only on one side 65 of the lag shield, such as 6.

In this form the lag shield 20 is provided with a collapsible head 21 by providing the head with the weakening apertures 22, 22 and the cutaway portions 122 and 122. If a portion of the head 21 extends out from the hole 9 in the support 10, it will be collapsed by the lag screw in the manner previously described in connection with the other forms.

In Figures 16 to 21 I have shown my invention applied to ductile bolt anchors or shields.

In this modification the bolt anchor shield 36 is preferably formed of a plurality of tines 37, 37 and an integral collapsible head 38. The head is made collapsible by any suitable means such as by forming the large slots or apertures 39, 39 in the head.

In practice when it is found that the end of the collapsible head 38 extends outward slightly from the hole 9 in the support 10, after the shield is partially expanded, Figure 20, it is not necessary to take down the fastening and relocate it in the hole. Simply by further screwing the screw 40 into the shield 36, the head 38 will be collapsed, as shown in Figure 21, thereby permitting the work 11 to be brought up flush against the surface 12 of the support, as described at length in connection with the other forms.

It will be noted that the maximum expansion of my bolt anchor is at, or near, the lower end of the hole in the wall or other support, and that there is practically little or no holding or gripping expansion in the hole near the surface of the wall.

This is very important because if the surface of the wall is formed of friable material, as is often the case, and any considerable portion of the expanding strains are exerted at or near the outer end of the hole, the surface 100 of the wall will be cracked, or chipped, or marred, making an unsightly job.

Moreover, by having the maximum expansion of the bolt anchor at or near the bottom of the hole, makes a stronger fastening in 110 that the expansion is exerted where the wall is strongest.

When the head is collapsed, as in Figures 7 and 21, there is practically little or no strain thrown on the walls of the hole near the surface of the wall or other support. Such slight pressure that may be thrown on the wall of the hole near the surface, by collapsing the head, to permit the work to be drawn up flush with the surface of the wall, are insignificant 115 and inconsequential, and are not relied upon to secure my bolt anchor in the hole. They are sufficient, however, to prevent teetering.

It will, further, be noted that in my bolt anchor the expansion is radial and immediate, when the screw or bolt is screwed into it. The bolt anchor is immediately held fast to the walls of the hole and its position in the hole is fixed. The main gripping portions of my bolt anchor do not later slide with rela- 120 130

tion to the walls of the hole. A portion, the weakened head, does move with relation to the walls of the hole, but this weakened head is not the main gripping portion of the bolt anchor. It is simply crushed, bent, or flexed between the fast gripping surfaces, securely expanded near the bottom of the hole, and the head of the bolt or screw, or the work supported. This bending or flexing of the head, if it does touch the walls of the hole, sets up only a minor or inconsequential grip which is not relied upon to secure the bolt anchor in the hole, but does prevent teetering of the bolt anchor.

15 The advantages of this construction have been previously pointed out in the specification.

Having thus described this invention in connection with illustrative embodiments 20 thereof, to the details of which I do not desire to be limited, what is claimed as new and what is desired to secure by Letters Patent is set forth in the appended claims.

What I claim is:

25 1. A new article of manufacture comprising a bolt anchor having a plurality of pivoted inner rigid, noncollapsible, radially operative expanding members provided with outer integral collapsible heads to permit a portion of the heads of the pivoted members which may protrude from a hole of insufficient depth in the wall or other support, to be collapsed, while the rigid noncollapsible portions of the pivoted members are firmly and immovably held within the hole, that the work supported may be brought up flush against the surface of the wall, even though the hole has been negligently drilled, thereby avoiding the necessity of removing the bolt 40 anchor and work, and redrilling the hole to the proper depth.

2. The combination in a bolt anchor having inner rigid, noncollapsible radially operative expanding members provided with a tapered 45 axial bore and with an outer integral collapsible head, to permit a portion of the head which may protrude from a hole of insufficient depth in a wall or support to be collapsed while the rigid, noncollapsible portion is firmly and immovably held within the hole, means to secure the said rigid, noncollapsible members together, and a bolt adapted to engage with the walls of the tapered axial bore to radially expand the said rigid expanding 50 members, that the work supported may be brought up flush against the surface of the wall even though the hole has been negligently drilled, thereby avoiding the necessity of removing the bolt, bolt anchor, and work, and redrilling the hole to the proper depth.

3. In combination a tubular expansion shield formed of two halves having a tapered and threaded interior bore and a lag screw, which when turned into the shield will first 65 create a rigid immovable expansive grip at

the inner end of the shield, leaving the outer end of the shield with a slideable fit in the hole, a latticed, collapsible formation at the outer end of the shield, which, if part of the shield is accidentally set outside the wall will later 70 be drawn inwardly with a slideable, collapsible movement when that portion is compressed between the head of the lag screw and the fixed expanded rigid portion of the shield at its inner extremity until the work being 75 attached is drawn up tight against the surface of the wall.
